UNITED STATES PATENT OFFICE

WALTER S. AUSTIN, OF GRAND RAPIDS, MICHIGAN

TWO-SPEED AXLE GEARING

Application filed February 20, 1928. Serial No. 255,524.

This invention relates to what may be termed a two-speed axle drive for the rear axles of automobiles, the design of the invention being such that the relative speeds of the drive may be transmitted to the rear axle shaft in two different relations, with consequent economy in use and additional comfort in operation. It is an object and purpose of the present invention to make an improved construction of this character which, while not broadly new and under the domination of my Patent No. 1,091,618, granted March 31, 1914, contains many features of construction of automobiles, making use of many of the parts thereof where the invention is applied, thereby keeping the cost at the lowest terms. Furthermore, the design and appearance of the automobile is not changed in any respect, as no cumbersome or unsightly parts are used. In fact one important feature of the invention resides in the solution of the problem of making the device practical and workable within the limits of the space in which the mechanism must be installed.

Many other objects and purposes, with novel constructions and arrangement of parts for obtaining the same, will be apparent as an understanding of the invention is had from the following description taken in connection with the accompanying drawings, in which,

Fig. 1 is a fragmentary horizontal section through the differential housing and the adjacent portions of the rear axle housing and driving shaft housing, my invention being installed in relation thereto.

Fig. 2 is an elevation of the front end of the smaller of the driving pinion sleeves used in the construction.

Fig. 3 is a central longitudinal section therethrough.

Fig. 4 is a partial vertical section and elevation illustrating the rear bearing for the driving shaft of the mechanism which is mounted at the back end and substantially in alignment with the propeller shaft.

Fig. 5 is a transverse section substantially on the plane of line 5—5 of Fig. 1, looking in the direction indicated by the arrows.

Figs. 6 and 7 are similar transverse sections

both taken on the plane of line 6—6 of Fig. 1 but looking in opposite directions, Fig. 6 looking toward the front as indicated by the arrows and Fig. 7 toward the rear.

Fig. 8 is a transverse vertical section substantially on the plane of line 8—8 of Fig. 1.

Fig. 9 is a side elevation of the driving shaft extended or located at the rear of and connected to the propeller shaft of the automobile, it being formed with clutch elements therein.

Figs. 10 and 11 are opposite end elevations thereof.

Fig. 12 is a fragmentary vertical section therethrough.

Fig. 13 is a central vertical section of the movable clutch member which is slidably mounted on the shaft member shown in Fig. 9.

Figs. 14 and 15 are opposite end elevations thereof.

Fig. 16 is a side elevation of said movable clutch member.

Fig. 17 is a longitudinal vertical section through the pinion sleeve carrying the larger pinion which is mounted around the movable clutch member, and

Fig. 18 is an end elevation thereof.

Like reference characters refer to like parts in the different figures of the drawings.

In the construction shown, housings 1 for the parts 2 of the rear axle shaft are provided which are enlarged as indicated at 1a to pass around the differential gearing housing and the ring gears associated therewith, the same being open at their front and rear sides, being closed at the rear by removable housing member 3 fastened by means of screws 4 to the rear axle housing. A spacing ring and gasket 5 may be interposed between the parts as shown in Fig. 1. A housing 6 for the clutch control mechanism of the two-speed axle drive is secured by similar cap screws at the front and closes the front opening. The housing 6 terminates at its forward end in a sleeve 7 into which the rear end of the housing 8, located around the propeller shaft 8a, extends being suitably secured therein.

The housing 6 described is equipped with

suitable bearing carrying portions 9 at its rear end which extends rearwardly and are completed by semi-circular clips 10 whereby suitable housings for ball bearings 11 are provided which may be adjusted as to position by suitable adjusting devices 12, shown in Fig. 1, the constructive detail of which is of no importance in the present invention. The bearings 11 serve to rotatably carry and support the differential housing 13 into which the opposite ends of the parts 2 of the rear axle extend. The differential housing has a circular web 14 extending therefrom adjacent one end, to which two ring gears 15 and 16 are permanently secured by suitable cap screws 17 as fully illustrated in Fig. 1. The ring gear 15 is of smaller diameter than the ring gear 16 and lies inside of the plane of the gear 16, both of the gears 15 and 16 extending into the housing 6.

A supporting member 18 lies across the housing 6, being located in a vertical plane and secured in place by suitable cap screws 19 (see Fig. 4) which thread into bosses projecting from the inner side of said housing 6. Substantially at its middle point it is formed into a ring 20 for the housing of a suitable ball bearing 21. The ring gear 15 passes around the ring 20 at one side thereof and the center of the ring 20 lies in line with the axis of the drive shaft.

A second ball bearing 22 is mounted in the housing 6 adjacent its front end back of the rear end of the integral sleeve 7 on said housing. The two bearings 21 and 22 carry a drive shaft 23 which is connected in any suitable manner with the shaft 8a. The drive shaft 23, a short distance back of its front end, is enlarged in diameter and is milled at spaced apart points so as to make three spaced apart splines, indicated at 24 on the shaft, back of which are three spaced apart radially projecting fingers 25 from each of which, at their outer sides and at points between the front and rear ends thereof, lugs 26 project. Back of the fingers 25 the shaft 23 is reduced somewhat in diameter for a distance making section 27, while back of the rear end of the section 27 it is still further reduced, as indicated at 28, for mounting in the ball bearing construction 21 previously described. The ball bearing construction 22 is located around the shaft 23 at the front ends of the splines 24. A sleeve 29 is located around all of the fingers 25 and at its front end is provided with suitable notches into which the lugs 26 extend to lock the sleeve with the drive shaft. The rear end of the sleeve 29 extends a short distance back of the rear ends of the fingers 25, as shown in Fig. 12.

A clutch member in the form of a sleeve 30 is slidably mounted on drive shaft 23. The rear portion of the sleeve is reduced in size and is slotted lengthwise for a portion of its length in a plurality of spaced apart points

whereby three clutch fingers 31 are provided which pass through the slots between the outstanding fingers 25 on the shaft 23 and under the sleeve 29 previously described. From the sleeve 30, substantially at its juncture with the fingers 31, other radial fingers or clutch elements 32 extend radially outwardly being spaced from each other the same angular distances that fingers 31 are spaced apart. It will be noted that the rear ends of the fingers 31 are cut with a backward lead 33 while the front sides of the clutch part or fingers 32 are cut with a forward lead, as indicated at 33a.

Over the movable clutch sleeve and the fingers 31 and 32 extending therefrom, a member is located comprising a sleeve-like portion 34 which, at its rear part, is machined to make a bevelled pinion 35 as shown in Fig. 17. This sleeve is formed with an annular recess 36 at its inner side and adjacent its front end the recess is large enough to receive the radially projecting clutch fingers 32; and at its front end is formed with a plurality of inwardly extending clutch fingers 37 spaced from each other proper distances in order that the fingers 32 may be received between them when the clutch is in its forward position. At its rear end the pinion sleeve 34 has an inwardly extending annular lip 38 with a bearing face 39 which bears against the rear end of the sleeve 29. The sleeve 34 is mounted for free rotative movement on the sleeve 29. It is provided that the inner diameter of the fingers 37 shall have a loose bearing on the outside of the sleeve 30. This has the effect of a longer bearing for the large pinion and keeps it from rocking as will later appear.

A small pinion sleeve 40 with pinion teeth 105 thereon is located over and loosely mounted on the extension 27 of the shaft 23, and is in mesh with the smaller ring gear 15, while the pinion 35 formed at the rear end of sleeve 34 is in mesh with the outer and larger ring gear 16. The front end of the small pinion sleeve 40 is machined to provide three forwardly extending clutch fingers 41 between which the rear ends of the fingers 31 of the movable clutch member are received when the clutch member is in its rearward position.

A yoke 42 connects with the front end 30 of the movable clutch member and a rod 43 slidably mounted and extending through the housing 6 is attached to the yoke whereby the movable clutch member may be shifted to three positions. In the forward position, the fingers 32 will be between the fingers 37 on the larger pinion sleeve and a driving of the rear axle takes place from shaft 23 through the slidable clutch member 30 to the larger pinion and thence to the ring gear 16. At the other extreme position of movement of the clutch member, fingers 31 are engaged by the fingers 41 of the small pinion sleeve 40 where-

by there will be a drive from the shaft 23 through the smaller pinion to the ring gear 15. At an intermediate position, and the one shown in Fig. 1, the clutch fingers 31 and 32 are not engaged with their pinion sleeves and the mechanism is neutral whereby shaft 23 may rotate continuously without in any way affecting either of the ring gears 15 or 16.

The construction described is very practical and operative in every way. It is a design of construction which greatly reduces the space necessary for the adaption of a two-speed axle drive to automobiles, particularly those of the smaller type, large numbers of which are now commercially manufactured. In fact, one very important feature of this invention in this connection is that the problem necessarily involved to make the construction workable and practical within the limits of space in which the mechanism must work, is fully and completely solved by this construction without in any way enlarging or making heavier the various housings which are used on automobiles for covering the differential gearing, the rear axle and the drive shaft; while the parts are given the necessary strength and durability to render the construction capable of standing the long time service it must undergo without breakage if it is to be successful. The bearing at 21 must have certain size and durability for success and to obtain this it is located partly within the inner ring gear 15. The clutch construction described is very practical and serviceable and is designed to occupy the very smallest space without sacrifice of strength and durability. The provision of the larger ring gear on the outside to be driven by the larger pinion, and the smaller ring gear on the inside to be driven by the smaller pinion, coupled with the clutch structure described so as to alternately connect the drive shaft with the two ring gears, is also a feature of the invention and one far beyond the obvious or the province of a designer having no problems of limited space to consider. And in the present case the space is very restricted and the structure must be practically operative and workable within such space. In addition a very important feature of the invention is that the pinions rotate on the drive shaft only when free of load, and always, when under load, they turn with the shaft, thus eliminating heavy friction wear and adding to the life of the construction. The lead indicated at 33 and 33a on the clutch fingers 31 and 32 makes the connection of the clutch with either driving pinion very simple and easy, and the lead is reversed with respect to the two fingers 31 and 32 by reason of the fact that when the mechanism is driven by pinion 35, the pinion sleeve 40 is turned freely on the extension 27 of shaft 23 faster than the shaft on which the clutch member is carried 65 is turning, the opposite being true with re-

spect to the larger pinion sleeve 34 which, when a connection is made between it and the clutch fingers 32 is rotating slower than said shaft 23.

It will be noted throughout that the clutch sleeve 30 has three spaced apart fingers 31 to engage between three cooperating fingers 41 on the small pinion sleeve 40 and that the radially projecting fingers 32 are also three in number to engage between the three inwardly extending clutch fingers 37 on the larger pinion sleeve 34. This a very important feature of the present invention. No other number of fingers in the clutch engaging elements of the construction will produce a like desirable result. With the use of the three finger construction throughout not only is there a greater strength to the contacting parts of the clutch elements but it lends itself to a perfect seating of the fingers of the clutch sleeve 30 with all the cooperating fingers 41 or 37 on the two pinion sleeves which cannot be obtained with any other number of clutch fingers.

It will be noted that the housing 6, the bearings 11, the differential gear housing 13 with the ring gears 15 and 16, the shaft 23 and the pinions and clutch mechanism mounted thereon may all be assembled as a unit and then assembled with the rear axle 90 housing 1 by passing the ring gears through the front and rear openings in the axle housing, the two parts 2 of the rear axle being inserted and assembled with the differential housing 13 by moving the same longitudinally 95 into connection therewith. Thereafter the shaft 8a with its housing 8 may be connected with the front ends of the housing 6 and the drive shaft 23 respectively.

This provides a very economical and simple means of assembly and a practical manufacturing construction whereby simplicity and economy is attained.

The structure described is a preferred form of construction and one which has proved very practical in all respects. The invention, however, may be embodied in other forms and I do not wish to be restricted to the specific form shown. For instance, while the shaft 8a and the drive shaft 23 are shown 110 as connected by a sleeve in alignment with each other, the sleeve form of connection is no way essential to the invention and any other suitable form of connection, for instance the universal joint, may be used quite 115 as well. The invention is defined in the appended claims and is to be considered comprehensive of all forms of structure coming within the scope thereof.

I claim:

1. In a mechanism of the class described, a drive shaft for automobiles formed between its ends with an annular enlarged portion slotted longitudinally at a plurality of spaced apart places, a sleeve located around 130

and secured to said annularly enlarged portion of the shaft, a second sleeve mounted on the shaft and slotted for a part of its length to provide fingers to pass through 5 said slots in the drive shaft underneath the first sleeve, said second sleeve also having an annular enlargement which is slotted to make outwardly extending radial fingers, a pinion loosely mounted at the rear end of 10 the drive shaft with which the rear ends of the first fingers engage on movement of the second sleeve in one direction, said pinion being formed at its front end with recesses for reception of the ends of the first fingers 15 of said second sleeve, a third sleeve formed at one end with a larger pinion loosely mounted on the first sleeve and around the second sleeve and formed at the end opposite its pinion end with spaced apart inwardly 20 projecting lugs between which the radial fingers on the annular enlarged portion of the second sleeve are adapted to pass on movement of the second sleeve in the opposite direction, and means for manually moving said 25 second sleeve back and forth.

2. A construction containing the elements in combination defined in claim 1, said third sleeve at the pinion end thereof being formed with an annular inwardly extending lip 30 against the inner face of which the rear end of the first sleeve on the propeller shaft bears.

3. In a gearing mechanism, a shaft formed between its ends with an enlarged portion, a sleeve fixed to the enlarged portion and overhanging the same, a pinion loosely mounted upon said sleeve, another pinion loosely mounted upon the said shaft, said second pinion having a portion of its bearing upon the shaft under the said overhanging sleeve, 40 means for clutching either of the pinions to the said shaft and gears meshing with the respective pinions.

4. In a device of the type described, a driven shaft having spaced apart protuberances extending radially therefrom, a pinion revolvably mounted upon said protuberances, a sleeve rigid with the pinion extending toward the shaft at one side of the said protuberances, a second pinion mounted on 50 the shaft at the opposite side of the protuberances relative to the sleeve, and clutch means slidable upon the shaft, said clutch means being engageable with the said sleeve and also extending between said protuberances and beneath said first pinion whereby it may be engaged with the second pinion for the purpose described.

In testimony whereof I affix my signature.
WALTER S. AUSTIN.
